UNITED STATES PATENT OFFICE.

GEORGE A. GEMMER AND CLARENCE E. CAMPBELL, OF NEWARK, NEW JERSEY.

TIME ELECTRIC SWITCH.

Application filed October 6, 1926. Serial No. 139,836.

This invention relates in general to electric switches of the type automatically opening or closing electric circuits after a predetermined period of time has elapsed, and 5 more particularly to such a switch especially adapted for use with radio receiving sets for controlling the battery current so that there can be no danger of the current being left turned on indefinitely as is now frequently the case when the operator forgets to 10 throw off the usual manually operated switch.

One object of the invention is to provide an electric switch of the character described 15 in which operation of the switch is controlled by a gravity influenced piston movable in a cylinder containing a liquid such as oil which retards movement of the piston, the switch being actuated when said piston 20 has moved a certain distance so that the speed of movement of the piston determines said period of time which must elapse before the switch is operated.

Another object is to provide a novel and 25 improved electric switch of this character wherein the speed of movement of said piston may be predetermined or controlled so that the period of time during which it is desired that the switch shall be open or 30 closed may be varied.

A further object is to provide such an 35 electric switch which includes a pair of terminals the circuit through which is closed by a conducting liquid such as mercury and wherein the mercury is displaced or moved 40 into or out of contact with at least one of said terminals by means controlled or actuated by said piston when the piston reaches the limit of its movement.

45 Other objects are to provide a time electric switch including a cylinder having a piston movable longitudinally thereof, and novel and improved means for tiltably mounting said cylinder between its ends on a horizontal axis; to provide a pair of electric switch contact elements at each end of said cylinder and mercury for normally closing the circuit between said contacts which is displaced from contact with at least one 50 of said contacts by means carried by said piston when the piston reaches its limit of movement, and to obtain other results and advantages as may be brought out by the following description.

55 Referring to the accompanying drawings,

in which corresponding and like parts are designated throughout the several views by the same reference characters,

Figure 1 is a front elevation of a time 60 switch embodying the invention;

Figure 2 is a transverse vertical sectional view, taken on the line 2-2 of Figure 1, showing the switch in position to close the circuit;

Figure 3 is a horizontal sectional view, 65 taken on the line 3-3 of Figure 2;

Figure 4 is a sectional side elevation showing the switch in open position;

Figure 5 is a view similar to Figure 1 showing a modified form of the invention; 70

Figure 6 is a sectional rear elevation of the switch shown in Figure 5, showing the switch in closed position;

Figure 7 is a transverse vertical sectional view, taken on the line 7-7 of Figure 6, 75 and

Figure 8 is a view similar to Figure 7 showing the switch in open position.

Specifically describing the embodiment of the invention illustrated in Figures 1-4, 80 inclusive, the reference character 1 designates a tube or cylinder of some electrical insulating material such as glass, which is fast secured in a transverse opening 2 in a block 3 which is mounted upon a stub 85 shaft 5 arranged at substantially right angles to the axis of the tube 1 and substantially centrally of the length thereof. The shaft 5 is horizontally journaled in any suitable manner upon a support 6 which may be the 90 front wall of a casing 7 within which the tube 1 is housed, and the shaft is provided exteriorly of the casing or support 6 with a knob or the like 8 whereby the shaft may be rotated. Interposed between the block 95 3 and the support 6 is a friction washer 9 which serves to hold the block in any adjusted position to which it is moved by rotation of the shaft 5. Obviously, with this construction, the axis of the tube 1 may be 100 disposed at any desired angle to the horizontal by merely rotating the shaft 5.

Within each end of the tube 1 is fitted a tubular electrical conducting member 10. Preferably this member 10 is frictionally 105 secured within a tubular cork bushing 11 which is in turn frictionally fitted within the tube 1, whereby a liquid-tight connection of the conducting member 10 to the tube 1 is secured. A plug 12 preferably 110

formed of cork is frictionally fitted within the outer end of the conducting member 10 and has mounted therein an electric conducting wire 13 which projects into the tube 1 substantially co-axially with the conducting member 10.

A piston 14 is reciprocably mounted within the tube 1 to move by action of gravity from one end thereof to the other, and a tubular circuit breaking member 15 is secured fast to the piston substantially co-axially thereof as by means of a cork bushing 16, said circuit breaking member projecting substantially equidistantly beyond each end 15 of the piston 14 and having a plug 17 of any suitable material such as shellac at substantially its center. The ends of the piston 14 are recessed or cupped as at 18. The tube 1 is filled with a liquid such as oil, 20 and a quantity of mercury 19 is arranged in each end of the cylinder to cooperate with the respective electrical conducting members 10 and 13. It will be observed that the construction comprises in effect two electric 25 switches each of which includes a switch cup or recess formed by the respective tubular contact member 10 and the plug 12, the contact members 10 and 13 being in spaced and substantially co-axial relation, 30 and when the respective body of mercury 19 is arranged within the switch cup it makes contact with both contact members 10 and 13 so as to close the circuit there- 35 through.

In operation of the switch, with the tube 1 at any angle to the horizontal, one body of mercury will be located in the lowermost switch cup while the other body of mercury will be located in the corresponding recessed end 18 of the piston 14, as shown in Figure 2 of the drawings; and the piston 14 is influenced by gravity toward the lowermost switch cup. Assuming the piston 14 to be somewhere between the ends of the tube 1, 45 it will slowly move due to action of gravity and resistance to movement by the oil in the tube, until it reaches the lowermost switch cup. As the circuit breaking member 15 enters the cup it surrounds the central contact member 13 and bodily displaces the mercury therefrom so as to break the circuit through the switch, as shown in Figure 4 of the drawings. Obviously, the time necessary for the piston to move from one end 50 of the tube to the other may be varied by variation of the angularity of the tube from the horizontal or by variations in the viscosity of the oil. Assuming the switch to be in open position as shown by Figure 4 of the drawings, when it is desired to close the circuit, the tube 1 is reversed by rotation to the shaft 5 so that the switch which was first at the lower end of the tube is now at the upper end, whereupon the lowermost 55 body of mercury drops to the lowermost

switch cup and the piston begins its descent in the tube. Preferably the operating knob 8 is formed with a pointer 20 cooperating with suitable indicia 21 for indicating the position of the tube 1, said pointer preferably being at substantially right angles to the axis of the tube, as shown.

The conducting members 12 and 13 of each switch cup are connected to binding posts 22 and 23 by means of wires 24, the 75 contact members 13 of both switches being connected to one binding post and the contact members 10 of both switches being connected to the other binding post. Also, the block 3 may be formed with transverse openings 25 with which communicate longitudinal openings 26 for supporting the wires and preventing tangling thereof incident to rotation of the tube 1.

Obviously, the casing 7 may be dispensed 85 with and the cover 6 may be supplanted by any other suitable support, such as the panel board of a radio receiving set.

A modified form of the invention is shown in Figures 5-8, inclusive, and includes a 90 tube 30 similar to the tube 1 and mounted in a block 31 fast to a shaft 32 journaled in a bearing 33 upon any suitable support such as a panel board 34. The shaft 32 is rotatable by a knob 35. The tube 30 is substantially balanced upon the block 31, that is, the shaft 32 is disposed substantially centrally of the length of the tube; and the tube is filled with oil or the like and has reciprocable therein a piston 36. The block 31 has 100 mounted therein a switch cup 37 within which is a quantity of mercury 38 and into which are fitted electrical conducting members or switch contacts 39 and 40. The contact members 39 are preferably parallel and so arranged that when the cup 37 is in one position the mercury contacts with both said members, while when the cup is in another position the mercury by action of gravity is 105 out of contact with one of said members.

In operation of the switch, the tube 30 is disposed at an angle to the horizontal, preferably 45 degrees, and the circuit through the contact members 39 and 40 is made by the mercury 38, as shown in Figure 6 of the drawing. For holding the tube 30 in this position we may employ a spring detent 41 having a finger 42 to engage a notch 43 on a detent plate 44 fast secured to any suitable support such as the panel board 34. The necessary tension or friction is supplied by adjustment of a thumb nut 45 mounted upon a screw 46 which passes loosely through an opening 47 in the detent strip 41. Assuming the piston 36 to be somewhere between the ends of the tube 30, it will move slowly by action of gravity toward the lower end of the tube, and when it reaches a point adjacent said lower end its weight will overcome the resistance produced by the spring detent 120 125 130

41 and force the finger 42 out of the notch 43, whereupon the block 31 and the tube will rotate until the axis of the tube is substantially vertical. Movement of the tube into this position is limited by a stop shoulder 50 on the detent plate 44 which is engaged by the edge of the spring detent strip 41. This movement of the block 31 tilts the mercury cup 37 so that one of the contact members 39 or 40 is moved out of the mercury, the mercury of course maintaining a constant level by action of gravity. The switch is therefore in open position as shown in Figure 8 of the drawings. Assuming the switch 10 to be in open position as shown in Figure 8, to close the switch the knob 35 is rotated through an angle of 135 degrees which reverses the tube 30 and locates the piston 36 at the upper end thereof, at the same time causing the mercury 38 to contact with both of the members 39 and 40. Obviously, two sets of detent notches and stop shoulders 43 and 50, respectively, will be provided, one set at each side of a vertical axial plane of 20 the shaft 32, as shown in Figure 6 of the drawings.

While we have shown two embodiments of our invention and illustrated certain details of construction, it will be understood that this is primarily for the purpose of illustrating the principles of the invention and that many modifications and changes may be made in the details of construction without departing from the spirit or scope of the invention. Therefore, we do not desire to be understood as limiting ourselves except as required by the following claims when construed in the light of the prior art.

Having thus described the invention, what we claim is:

40 1. A time electric switch comprising a cylinder having a piston therein movable by action of gravity, a switch cup having a pair of spaced and insulated electrical contact members therein and mercury to contact with both of said members and movable out of contact with at least one thereof, and means actuated by said piston when it reaches a certain point in said cylinder for displacing said mercury from at least one of said contact members.

45 2. A time electric switch comprising a cylinder having a piston therein movable by action of gravity, a switch cup having a pair of spaced and insulated electrical contact members therein and mercury to contact with both of said members and movable out of contact with at least one thereof, and means for mounting said cylinder and said switch cup so that when said piston reaches a certain point in said cylinder said mercury is displaced from at least one of said contact members.

50 3. A time electric switch comprising a hollow cylinder having both ends closed, a piston movable in said cylinder, means for tilt-

ably mounting said cylinder on a horizontal axis so that the cylinder may be disposed with its axis at an angle to the horizontal and alternately reversed to cause said piston to move by action of gravity from one end of the cylinder toward the other, a pair of spaced and insulated electric switch contact members projecting into said cylinder, a body of mercury in said cylinder to contact with both of said contact members and close a circuit and displaceable out of contact with at least one of said members, and means on said piston for so displacing said mercury when the piston reaches a certain point in the cylinder.

55 4. A time electric switch comprising a cylinder having a piston therein, means for tiltably mounting said cylinder on a horizontal axis so that said cylinder may be disposed with its axis at an angle to the horizontal to cause said piston to move in said cylinder by action of gravity from one end to the other and vice versa, a switch cup or recess at one end of said cylinder having a pair of spaced and insulated electrical contact members therein, and mercury within said cup to contact with both of said contact members to close a circuit and movable out of contact with at least one of said members, said piston having a portion formed with a recess to enter said cup and surround one of said contact members to displace said mercury from said one of said contact members when the piston reaches a certain point in said cylinder.

60 5. A time electric switch comprising a cylinder having a piston therein, means for tiltably mounting said cylinder on a horizontal axis so that said cylinder may be disposed with its axis at an angle to the horizontal to cause said piston to move in said cylinder by action of gravity from one end to the other and vice versa, a switch cup or recess at one end of the cylinder including an annular or sleeve-like electric contact member and a second electric conducting member projecting into said cup or recess from the bottom thereof in spaced and insulated relation to said annular member, and a body of mercury to contact with both of said contact members to close a circuit, said piston having a portion formed with a recess to enter said cup and surround the second-mentioned contact member and displace said mercury from contact therewith and open the circuit.

65 6. The time electric switch member set forth in claim 4 in which said cylinder has a non-conducting liquid through which said piston moves.

70 7. The time electric switch member set forth in claim 5 in which said cylinder has a non-conducting liquid through which said piston moves.

75 8. A time electric switch comprising a

- hollow cylinder having both ends closed and capable of being disposed with its axis at an angle to the horizontal and alternately reversed, a piston movable in said cylinder from one end toward the other by action of gravity, a pair of spaced and insulated electric switch contact members projecting into said cylinder, and a body of mercury in said cylinder to contact with both of said contact members and close a circuit and displaceable out of contact with at least one of said members, said piston being formed to so displace said mercury when the piston reaches a certain point in said cylinder.
- 15 9. A time electric switch comprising a hollow cylinder having both ends closed and capable of being disposed with its axis at an angle to the horizontal and alternately reversed, two spaced pairs of spaced and insulated electric switch contact members projecting into said cylinder, a piston movable in said cylinder from one end toward the other and vice versa by action of gravity, and a body of mercury at each side of said piston for contacting with one of said pairs of contact members to close the circuit therethrough and displaceable out of contact with at least one of said contact members of the respective pair to open the circuit, said piston being formed to so displace said bodies of mercury when it reaches certain points in said cylinder.
- 20 10. A time electric switch comprising a hollow cylinder having both ends closed and capable of being disposed with its axis at an angle to the horizontal and alternately reversed, a switch cup or recess at each end of said cylinder including an annular or sleeve-like electric switch contact member and a second contact member arranged within and in spaced and insulated relation to said annular contact member, a piston movable in said cylinder by action of gravity from one end to the other, and a body of mercury movable by gravity in said cylinder between each side of said piston and the corresponding end of the cylinder to cooperate with the respective pair of switch contact members to open and close a circuit, said piston having at each end a portion formed with a recess to enter the corresponding switch cup and surround the second-mentioned contact member to displace the mercury from contact therewith.
- 25 11. A time electric switch comprising a hollow cylinder having both ends closed and capable of being disposed with its axis at an angle to the horizontal and alternately reversed, a pair of spaced and insulated electric switch contact members projecting into said cylinder, and means for electrically connecting said contact members, said means being displaceable from at least one of said contact members to disconnect said members, said piston being formed to so displace said means when the piston reaches a certain point in said cylinder.
